UNITED STATES PATENT OFFICE.

MALCOLM B. JACKSON, OF VICTORIA, BRITISH COLUMBIA, CANADA.

VERTICAL FILE-FOLDER.

1,076,582.

Specification of Letters Patent.

Patented Oct. 21, 1913.

Application filed December 18, 1912. Serial No. 737,422.

To all whom it may concern:

Be it known that I, MALCOLM B. JACKSON, a subject of the King of Great Britain, and a resident of Victoria, in the Province of British Columbia and Dominion of Canada, have invented a new and Improved Vertical File-Folder, of which the following is a full, clear, and exact description.

This invention relates to filing devices especially adapted for correspondence or other business papers, whereby such papers are maintained in a substantially flat and better condition than usually.

Among the objects of the invention is to provide a filing device which will reduce the tendency to misfile papers, means being provided whereby each file is kept locked or closed in such a manner as to necessitate the opening of the file in order to introduce additional papers but which locking means is of such a simple nature as to require but a moment's expenditure of time.

A further object of the invention, incidental to the foregoing, is to provide a filing folder of such a nature that in case the file be dropped or left lying on a desk subjected to gusts of wind or the like, the papers will not have the tendency to slip out of place or be otherwise lost.

A still further object of the invention is to provide a filing device of a simple form and yet which will accommodate itself to the increased amount of correspondence to be contained therein without changing the dimensions of the front of the file which ordinarily carries the filing legend or destroying the symmetry or alinement of a series of such files in a cabinet.

The foregoing and other objects of the invention will hereinafter be more fully described and claimed and illustrated in the drawings forming a part of this specification in which like characters of reference indicate corresponding parts in all the views, and in which—

Figure 1 is a view of a folder made in accordance with this invention, the same being shown opened out; Fig. 2 is a front elevation of the same in one of the folded positions; Fig. 3 is a transverse vertical section, substantially on the line 3—3 of Fig. 2, showing the transverse form of the folder as indicated in Fig. 2; and Figs. 4 and 5 are views similar to Fig. 2, but showing the transformation in the form of the folder in accordance with the growth of the correspondence.

Referring particularly to the drawings, I show a folder comprising a front panel 10 and a rear panel 11. Said panels may be connected by any suitable material of a flexible nature. As herein illustrated, however, said parts are integral or formed of the same material throughout, but provided at the bottom with a plurality of parallel scores or weakened lines 12. The line 12' farthest from the rear panel 11 marks or determines the bottom edge of the front panel 10. In other words, the front panel in all embodiments of this invention will be comparatively stiff and the folder will rest upon a bottom of which the line 12' just referred to will be a boundary. The upper or outer portion of the panel 10 is designed to carry a filing legend such as indicated at 13, and such legend may be applied to an extension or tongue 14 located at any desired part of said panel. For reasons already indicated, it will be understood that the length or height of the panel represented by the distance from the tongue 14 to the line 12' will remain substantially constant. As the volume of correspondence increases, the thickness of the file will be increased in accordance with the additions along the bottom, or, as indicated in Figs. 4 and 5, in accordance with the successive spaces between the lines 12, and the rear panel 11 will be shortened accordingly. The shortening of the rear panel, however, is not objectionable, but it may be replaced by a wider one, if desired, as the file grows.

In order to provide a convenient temporary seal or lock for securing the front and rear panels together at their mouth and thereby prevent accidental displacement of papers, either at the time of filing or subsequently, I provide a flap 15 secured to one of the panels, preferably the rear panel, in any suitable manner, said flap being of a length sufficient to extend over the upper edge of the front panel and down to a certain distance over the front face, as shown in Fig. 2. A tape or other flexible connection 16 is adapted to coöperate with a holder 17, the latter being shown secured permanently to the front panel and the tape 16 being shown connected permanently to the end of the flap. This locking means therefore insures that the file and its contents will always be reasonably intact, and in order to insert or remove a paper from the file, the locking means must be loosened.

No matter, therefore, how full the file may become, when it is removed from the cabinet, all of the papers, either in the particular file operated upon or any of the other files, 5 will remain in place. As the thickness of the file increases, the front panel will remain of uniform size, but the growth will be accommodated by the extension of the bottom and the partial shortening of the flap 10 and rear panel, the tape 16, of course, paying out in accordance with such growth.

The flap 15 may be arranged in any desired place, but as indicated herein, I find it most satisfactory to apply it at the middle 15 portion of the folder. By this arrangement a single locking means for each folder is ordinarily sufficient, and hence the tongue 14 located preferably at one of the corners is not disturbed by the flap. The flap is 20 preferably of some suitable flexible material or it may constitute an extension of the rear panel, being suitably scored or broken to make it flexible. It will appear, furthermore, that the other parts of the folder may 25 be made of any suitable materials, and I do not wish to be limited to the particular form or dimensions illustrated except as may be required by the state of the art. The flap 15

may be of any width and when broken to make it flexible it may be suitably reinforced with fabric or the like to make it of sufficient strength. 30

Having thus described my invention, I claim as new and desire to secure by Letters Patent:—

The herein described filing device comprising a folder having a stiff front panel, a rear panel, flexible means connecting said panels, said flexible means constituting a base of variable width according to the 40 thickness of the file contents, and locking means temporarily securing the opposite edges of the panels together, said locking means comprising a flexible flap secured to one panel and extending over the edge of 45 the opposite panel and a flexible tape adapted to be snubbed around a holder carried by the other panel.

In testimony whereof I have signed my name to this specification in the presence of 50 two subscribing witnesses.

MALCOLM B. JACKSON.
